OTHER PUBLICATIONS

Applicant sold in the U.S. a battery similar to the one illustrated in Appendix A on Mar. 18, 2014.

Primary Examiner — Rosemary K Tarcza

Assistant Examiner — James Thorn, Sr.

(74) Attorney, Agent, or Firm — Michael Best & Friedrich LLP

(57) **CLAIM**

I claim the ornamental design for a battery, as shown and described.

DESCRIPTION

FIG. 1 is a perspective view of a battery according to an embodiment of the invention.

FIG. 2 is a front side view of the battery shown in FIG. 1.

FIG. 3 is a back side view of the battery shown in FIG. 1.

FIG. 4 is a left side view of the battery shown in FIG. 1.

FIG. 5 is a right side view of the battery shown in FIG. 1.

FIG. 6 is a top side view of the battery shown in FIG. 1; and,

FIG. 7 is a bottom side view of the battery shown in FIG. 1.

The elements shown in dashed lines are included for the purpose of illustrating environment and form no part of the claimed design. The dot-dash line in FIG. 3 illustrates a boundary between claimed and unclaimed subject matter, and forms no part of the claimed design.

1 Claim, 6 Drawing Sheets
